UNITED STATES PATENT OFFICE

152,161

DESIGN FOR A ROTARY WINGED AIRCRAFT

Frederick J. Knack, New York, N. Y., assignor to
Autogiro Company of America, Philadelphia,
Pa., a corporation of Delaware

Application May 25, 1946, Serial No. 130,063

Term of patent 14 years

(Cl. D71—1)

To all whom it may concern:

Be it known that I, Frederick J. Knack, a citizen of the United States, residing at 828 Crawford Ave., N. Y. city, in the county of Bronx and State of New York, have invented a new, original, and ornamental Design for Rotary Winged Aircraft, of which the following is a specification, reference being had to the accompanying drawings, forming a part thereof.

Figure 1 is a side elevational view of the rotary winged aircraft showing my new design.

Figure 2 is a front elevational view of the craft shown in Figure 1.

Figure 3 is a top plan view of the craft shown in Figure 1.

Figure 4 is a rear elevational view of the craft shown in Figure 1.

The characteristic features of my design reside in the portions shown by means of full lines in the drawing.

I claim:

The ornamental design for a rotary winged aircraft, as shown and described.

FREDERICK J. KNACK.
